TELEPRINTER CONSOLE CABINET

Wilhelm Winkler, Weil der Stadt, Germany, assignor to
International Standard Electric Corporation, New York,
N.Y., a corporation of Delaware

Filed Aug. 23, 1966, Ser. No. 3,564

Claims priority, application Germany Feb. 25, 1966

Term of patent 14 years

(Cl. D26—14)

Fig.1

Fig.3

Fig.2

Fig.5

Fig.4

FIGURE 1 is a perspective view taken from the front, top and right side of a teleprinter console cabinet showing my new design, the sideboard being shown in an extended position;

FIGURE 2 is an elevational view taken from the right side thereof;

FIGURE 3 is an elevational view taken from the left side thereof;

FIGURE 4 is a rear elevational view thereof; and

FIGURE 5 is a top plan view thereof.

The dominant features of my design reside in the portions shown in full lines.

I claim:

The ornamental design for a teleprinter console cabinet, substantially as shown and described.
